(57) **CLAIM**

The ornamental design for a microcurrent skin treatment device, as shown and described.

DESCRIPTION

FIG. 1 is a top front right isometric view of a microcurrent skin treatment device.

FIG. 2 is a bottom rear left isometric view of the microcurrent skin treatment device.

FIG. 3 is a front elevation view of the microcurrent skin treatment device.

FIG. 4 is a rear elevation view of the microcurrent skin treatment device.

FIG. 5 is a left side elevation view of the microcurrent skin treatment device.

FIG. 6 a right side elevation view of the microcurrent skin treatment device.

FIG. 7 is a top plan view of the microcurrent skin treatment device.

FIG. 8 is a bottom plan view of the microcurrent skin treatment device.

FIG. 9 is a top front right isometric detail view of the head or skin contact portion of the microcurrent skin treatment device of FIG. 1, showing the shallow surface pattern; and, FIG. 10 is a front detail view of the head or skin contact portion of the microcurrent skin treatment device of FIG. 1, also showing the shallow surface pattern.

The parallel lines at the transitions between surfaces of shallow patterns are intended to illustrate a transition that can include smooth rounding or bevel facets in the transition.

1 Claim, 7 Drawing Sheets
